(57) **CLAIM**

The ornamental design for a webcam, as shown and described.

DESCRIPTION

FIG. 1 is a front perspective view of a webcam showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged portion view taken from encircled portion labeled, “9,” in FIG. 1; and,

FIG. 10 is an enlarged portion view taken from encircled portion labeled, “10,” in FIG. 2.

The dashed-dot lines form the boundary of the enlarged portion view of FIGS. 9 and 10 in FIGS. 1, 2, 9, and 10 and form no part of the claimed design. The even dashed broken lines shown in the drawings are included for the purpose of illustrating portions of the Webcam that form no part of the claimed design.
